D. Reynolds,

Reciprocating Saw Mill,

N° 22,892,

Patented Feb. 8, 1859.

Witnesses

Inventor:
David Reynolds

UNITED STATES PATENT OFFICE.

DAVID REYNOLDS, OF OGDEN, INDIANA.

DEVICE FOR PREVENTING TREMULOUS VIBRATION OF SAW-GATES.

Specification of Letters Patent No. 22,892, dated February 8, 1859.

To all whom it may concern:

Be it known that I, DAVID REYNOLDS, of Ogden, county of Henry, and State of Indiana, have invented a new and Improved 5 Mode of Preventing the Saw-Sash from Trembling While in Motion in the Saw-Mill; and I do hereby declare that the following is a full and exact description thereof, reference being had to the accompanying drawings and to the letters of reference marked thereon.

The nature of my invention consists in securing to the framework in which the saw sash is worked a straight bar of iron, wood, 15 or other metal as near the saw as possible and near the middle of the lower part of the sash and passing through boxing, which fits it accurately, and when the sash plays up and down in the slides at the sides, or on the 20 fender posts, this straight bar prevents the saw being thrown backward and forward by the operation of the pitman it therefore cuts to much better advantage.

To enable others skilled in the art to make 25 and use my invention I will proceed to describe its construction and operation.

Figure 1 represents a perspective view of my improvement set in a frame which is constructed similar to any saw mill frame.

A represents the frame; B, B, the fender posts; C the saw gate as also represented in Fig. 2; D the rod for steadyng the saw sash and saw while in motion, as also represented in Fig. 2; E the boxing secured to the lower end of the sash through which the 35 bar D passes as also seen in Fig. 2. F F are two pieces of timber secured to the frame to which is attached the rod or bar D firmly. They are also shown in Fig. 2. G is the saw pitman as seen in Figs. 1 and 2. H 40 is the crank to which the pitman is attached. I is the shaft; J J the bearings for the shaft, to which the driving power may be attached.

Fig. 2 represents a sectional drawing as referred to above showing the sash, the pitman guide rod and its boxing with the two pieces of timber F, F.

What I claim as my invention and desire to secure by Letters Patent is—

Combining the guide bar D and boxing E 50 with the sash saw and fender posts for the purposes set forth and substantially as above described.

DAVID REYNOLDS.
